DESIGN FOR A PHOTOGRAPHIC ENLARGER

Hans R. Kossman, West Los Angeles, and Roscoe C. Hubbard, Culver City, Calif., assignors to Emby Photographic Products of California, Inc., West Hollywood, Calif., a corporation

Application August 29, 1939, Serial No. 86,922

Term of patent 3½ years

To all whom it may concern:

Be it known that we, Hans R. Kossman, a citizen of Germany, residing at West Los Angeles, in the county of Los Angeles, State of California, and Roscoe C. Hubbard, a citizen of the United States, residing at Culver City, county of Los Angeles, State of California, have jointly invented a new, original, and ornamental Design for a Photographic Enlarger, of which the following is a specification, reference being had to the accompanying drawing, forming a part thereof.

The characteristic features of our new design are a base having flat end faces flared outwardly toward the top, the flare being more pronounced at the front of the device, the front and rear portions of the base being curved panels following the flare of the ends, the base being surrounded by a cover having a horizontal portion and a downwardly inclined forward portion, a hexagonal drum or drums mounted in the base and having windows in the plane faces visible from the front, curved brackets adjacent each end of the base, and a housing rising above the brackets having plain side walls and a plain rear wall rounded at the top and a flat front wall with windows therein.

We claim:

The ornamental design for a photographic enlarger, as shown and described.

HANS R. KOSSMAN.
ROSCOE C. HUBBARD.
